(57) **CLAIM**

The ornamental design for a handset camera, as shown and described.

DESCRIPTION

FIG. 1 is a perspective front view of a handset camera showing my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken line showing of the environmental structure of the handset in the drawing figures is for illustrative purposes only and forms no part of the claimed design. The depicted location and orientation the handset camera (shown in solid lines) relative to the boundary of the rear panel of the handset (shown in broken lines) is for illustrative purposes only and forms no part of the claimed design.
